(57) **CLAIM**

The ornamental design for a tread portion of a motorcycle tire, as shown and described.

DESCRIPTION

FIG. 1 is a perspective view of the front and left side of a tread portion of a motorcycle tire, it being understood that the tread pattern repeats itself uniformly throughout the circumference of the tire;

FIG. 2 is a front elevational view thereof, the top and bottom plan views being identical thereto;

FIG. 3 is a rear elevational view thereof;

FIG. 4 is a right side elevational view thereof;

FIG. 5 is a left side elevational view thereof;

FIG. 6 is an enlarged fragmentary front view thereof; and,

FIG. 7 is a cross-sectional view taken along the line 7—7 as shown in FIG. 6 thereof.

The elements shown in broken lines, including the peripheral boundary between the tire shoulder and sidewall, are for illustrative purposes only and form no part of the claimed design.
